UNITED STATES PATENT OFFICE.

PHILIP F. APFEL, OF SEATTLE, WASHINGTON, ASSIGNOR OF ONE-HALF TO WALDO E. MATHER, OF SEATTLE, WASHINGTON.

THERMOSTATIC SWITCH.

1,426,447.

Specification of Letters Patent. Patented Aug. 22, 1922.

Application filed April 4, 1921. Serial No. 458,375.

To all whom it may concern:

Be it known that I, PHILIP F. APFEL, a citizen of the United States, residing at Seattle, in the county of King and State of Washington, have invented certain new and useful Improvements in Thermostatic Switches, of which the following is a specification.

This invention relates to electric liquid heaters and, more especially, to thermostatically operated switches for controlling the supply of the heating medium therefor.

The main object of my invention is to provide an apparatus of this character with improved switch controlling means actuated by variations of the liquid temperature for regulating the electric current or heating medium to afford a substantially uniform temperature to the liquid during the operation of the heater.

Another object is to provide apparatus of this nature in which the thermostat and the associated switch are contained within a housing which is adapted to be connected with a pipe or other liquid conduit through which liquid may flow.

A further object is to provide a thermostatically operated switch provided with a novel means for indicating whether the switch is in its open or closed condition.

The invention consists in the novel construction, adaptation and combination of parts as will be hereinafter described and claimed.

35 In the accompanying drawings,—

Figure 1 is an elevational view, with parts broken away, showing an embodiment of the present invention applied to an electric water heating apparatus. Fig. 2 is a longitudinal vertical sectional view to an enlarged scale illustrating the thermostatic switch mechanism. Fig. 3 is a transverse sectional view through 3—3 of Fig. 2. Fig. 4 is a longitudinal sectional view showing a modified form of the invention.

50 In said drawings, the reference numeral 5 designates a shell or casing having water inlet and outlet openings at its opposite ends. As shown, said outlet extends through a threaded boss 6 which is connected with a hot-water service pipe 8.

The inlet to said shell is shown as an elbow 7 which is connected to the side outlet of a T-fitting 10 through which an electric heat-

ing element 11 extends into a water receptacle or tank 12.

Surrounding the element 11 in said T-fitting is a passage 13 affording communication between said tank and the shell 5. Interiorly of said shell is a liquid tight box having thin walls 14 of a high heat conducting metal which are spaced from the respective shell walls to provide water passages 15. A plate 16 serves as a removable wall for both the shell and the box and seats against packing 17 which prevents any leakage of water therat.

Said box constitutes a housing for a thermostat having a compound-plate 18 made of two metals which effect the bending of the plate by their unequal expansion by increments of heat. The thermostat plate has its ends seated against the ends 20 of rigid supports 21.

75 Centrally of its length, said thermostat plate is connected to a rod 22 which is guided for reciprocatory movements in members 23 and 24 of a frame which is rigid with the cover plate 16.

The frame member 24 is formed of an 80 electric insulating material and has secured thereto switch terminals 26 and 27 which are engageable by a switch contact or closure 25 provided on the rod 22 when the latter is suitably influenced by the action of the thermostat plate 18. 85 30 represents a helical spring interposed between said thermostat plate and a set collar 28 on the rod 22 to produce quick switch-opening movements to the contact 25 with respect to said switch 90 terminals.

The circuit wires 31 and 32 for the electric heater 11 extend into the thermostat box, one of said wires being divided and has the parts thereof respectively connected to the 95 switch terminals 26 and 27.

As illustrated in Fig. 2, the rod 22 is connected to an arm of a lever 33 which is fulcrumed intermediate its length by a pin 34 to said frame. This lever terminates in 100 blade elements 35 and 36 arranged to be protruded by the reciprocatory movements of the rod through slots 37 and 37¹ of the cover plate 16 to indicate the open or closed 105 positions of the switch contact as by means of suitable distinguishing colors or marks provided on the respective lever ends.

With the thermostatic switch connected

with an electric liquid heater and tank in the manner illustrated and described it operates automatically to control the flow of the electric current to the heater. When the 5 water in the tank cools, the thermostat plate 18 is influenced by such temperature reduction to enable the same to afford a flow of current to the electric heater. As the water becomes warmer the thermostat plate will 10 bow outwardly with an opening of the switch and cutting off the current to the electric heater.

By suitably regulating the above described switch controlling mechanism it is apparent 15 the switch may be controlled to open and close the heater current to maintain the liquid at an approximately predetermined temperature.

When the thermostatic switch is applied 20 as shown the thermostat will be actuated by variations in the temperature of the water in the tank even though no water is being drawn off through the pipe 8.

In Fig. 4 I have shown a housing 40 having 25 an inner box or receptacle 41 that is spaced from the walls thereof as at 42 and containing a thermostat member 43 of substantially the form shown. One end of the thermostat 43 is secured to the box 41 while 30 the other end is connected with a switch lever 44 which is fulcrumed on a pivot 45 in a switch housing 46.

The switch lever 44 carries a pin 47 which operates within a slot of an arm 48 which 35 carries a roller 50 on its lower end and is provided with a compression spring 51. The roller 50 rolls on an arcuate track-way 52 and is arranged to bridge the gap between two switch terminals 53 and 54 of a circuit 40 wire 55 that may extend to an electric heater.

When the interior of the receptacle 41 is cool the thermostat 43 will assume approximately the shape and position in which it 45 is illustrated with a consequent closed circuit; but as the receptacle 41 becomes heated,

the thermostat 43 straightens out thereby throwing the upper end of the lever 44 to the right and causing the switch roller 50 to move from the position in which it is shown in the drawing to the opposite end of the trackway 52.

As the switch lever 44 is moved from one inclined position to the other the roller 50 remains stationary until the pin 47 passes 55 a line extending through the centers of the roller 50 and the pivot 45, whereupon spring 51 acts to snap the roller to the opposite end of the trackway 52 for quickly opening or closing the circuit. 60

The device shown in Fig. 4 may be connected with a liquid heater in substantially the same manner as the device shown in the preceding figures.

Obviously changes in the form of construction of this apparatus may be resorted to within the scope of the following claim.

What I claim is,—

Apparatus of the character described, comprising a housing, a liquid-tight receptacle formed of relatively thin heat conducting walls disposed within said housing and spaced from the walls thereof to afford narrow passageways for liquid, liquid inlet and outlet means connected with said housing, 70 a thermostat plate disposed within said receptacle in close proximity to a wall thereof said plate being adapted to be bowed outwardly by a rise of temperature, a switch stem connected with the central portion of 75 said plate, spaced switch terminals adjacent said stem, a contact member on said stem for bridging the gap between said switch terminals, and means connected with the outer end of said switch stem for indicating 80 the open and closed position of said switch.

Signed at Seattle, Washington, this 17th day of March 1921.

PHILIP F. APFEL.
